Primary Examiner — Robert M Spear*Assistant Examiner* — Ryan Harvey(74) *Attorney, Agent, or Firm* — Troutman Sanders LLP;
Benjamin C. Wiles(57) **CLAIM**

The ornamental design for a weight, as shown and described.

DESCRIPTION

FIG. 1 is a perspective view of a weight of the present invention;
FIG. 2 is a front view of the weight of FIG. 1;

FIG. 3 is a back view of the weight of FIG. 1;

FIG. 4 is a side of the weight of FIG. 1;

FIG. 5 is another side view of the weight of FIG. 1;

FIG. 6 is a top view of the weight of FIG. 1; and,

FIG. 7 is a bottom view of the weight FIG. 1.

The broken lines are for the purpose of illustrating environment and form no part of the claimed design.
